United States Patent Office

Des. 207,449
Patented Apr. 18, 1967

207,449

DIGGER TOOTH UNIT

William W. Wilson, 6204 W. Canal Blvd.,
Shreveport, La. 71108

Filed July 1, 1966, Ser. No. 2,904

Term of patent 14 years

(Cl. D39—1)

FIG. 1 is a perspective view of a digger tooth unit showing my new design;

FIG. 2 is an exploded perspective view thereof;

FIG. 3 is a side elevation in a fully assembled condition;

FIG. 4 is a rear elevation as seen on line 4-4 of FIG. 3;

FIG. 5 is a front elevation thereof;

FIG. 6 is a bottom plan view thereof;

FIG. 7 is a top plan view thereof;

FIG. 8 is a top plan view of the lock pin member separately illustrated to clearly show the appearance thereof; and

FIG. 9 is a side elevation thereof.

I claim:

The ornamental design for a digger tooth unit, as shown and described.
